(57) **CLAIM**

We claim the ornamental design for a “combined laser light projector and remote control,” as shown.

DESCRIPTION

FIG. 1 is a perspective view of the combined laser light projector and remote control; and,

FIG. 2 is a front view of the combined laser light projector and remote control of FIG. 1;

FIG. 3 is a back view of the combined laser light projector and remote control of FIG. 1;

FIG. 4 is a right side view of the combined laser light projector and remote control of FIG. 1;

FIG. 5 is a left side view of the combined laser light projector and remote control of FIG. 1;

FIG. 6 is a top view of the combined laser light projector and remote control of FIG. 1; and,

FIG. 7 is a bottom view of the combined laser light projector and remote control of FIG. 1.

The nature and intended use of the article in which the design is embodied is the projection of light.
